TUNING FORK TYPE PERIODIC SWITCH

George E. Perreault, White Plains, N. Y., assignor
to Bell Telephone Laboratories, Incorporated,
New York, N. Y., a corporation of New York

Application October 28, 1947, Serial No. 782,528

5 Claims. (Cl. 200—90)

1

This invention relates to electrical relays and more particularly to relays of the tuning fork type.

The object of the invention is to provide an improved relay of the tuning fork type.

A feature of the invention resides in contact means provided in the relay.

Another feature resides in a supporting structure for a contact.

Another feature resides in a floating supporting structure for the tuning fork assembly.

In the drawing:

Fig. 1 is a view in perspective of a relay embodying this invention and with an operating coil exterior of the casing of the relay;

Fig. 2 is an enlarged view, in perspective and partly in section, of the relay;

Fig. 3 is a front view, partly in section, of a portion of the structure shown in Fig. 2;

Fig. 4 is a side view, partly in section, of the portion of the structure shown in Fig. 3;

Fig. 5 is a side view, partly in section, of the upper portion of the relay shown in Fig. 2; and

Fig. 6 is a view in cross-section of the relay and taken on the line 6—6 in Fig. 4.

The relay of this invention comprises a tubular casing 7 having an upper closed end 8. The casing 7 is supported endwise on a plug 9 in which are insulatingly supported pin-type terminals 10 and 11, portions of which project downwardly from the plug 9.

Supported at one end in the plug 9 and extending lengthwise within the casing 7 is a conducting bar 12 of non-magnetic material forming a support for a tuning fork structure 13 comprising the tines 14 and 15 of magnetic material. At one end the tines 14 and 15 are welded to and held in spaced relation by an apertured metal block 16 which forms the closed end of the tuning fork structure, the other end being free to move when the tines 14 and 15 are vibrated. The tine 14 is held in spaced relation with the conducting bar 12 by an apertured spacer plate 17. The closed end portion of the tuning fork structure 13 is supported near the upper portion of the conducting bar 12 and so that the tines 14 and 15 extend downwardly and about half the length of the conducting bar 12. The lower end of the conducting bar 12 extends into a relatively large recess 18 formed in the plug 9 and a pin 19 extending through a relatively large aperture 65 in the lower end of the conducting bar 12 and tightly into a transverse aperture 20 formed in the plug 9 serves to hold the conducting bar 12 floating in the plug 9. It will be seen that the lower end of the con-

2

ducting bar 12 is not rigidly held in the plug 9 but is permitted to move within the limitations of the relatively large recess 18 in the plug 9 and also to an extent permitted by the relatively large aperture 65 in the lower end of the conducting bar 12. The lower end of the conducting bar 12 is, therefore, in effect, floatably supported in the plug 9.

The upper end portion 21 of the conducting bar 12 extends through a relatively large aperture 22 formed in a spider-type supporting plate 23 which has angularly extending spaced leg members 24 extending into tight frictional engagement with inner surfaces of the casing 7. The spider-type supporting plate 23 rests loosely between the upper end of the tuning fork structure 13 and a bent retainer pin 25 and is held against undue upward movement on the conducting bar 12 by means of the bent retainer pin 25 extending transversely through the conducting bar 12 and above the spider-type supporting plate 23. It will be seen that the upper portion of the conducting bar 12 is not rigidly held but is permitted to move within the limitations of the relatively large aperture 22 and that the upper portion of the conducting bar 12 and the upper portion of the tuning fork structure 13 are, in effect, floatably supported in the spider-type supporting plate 23.

A permanent magnet 26 is mounted on the conducting bar 12 in the vicinity of and below the free ends of the tines 14 and 15. A pole-piece 27 of magnetic material extends from one end of the permanent magnet 26 and into the space 28 between the free ends of the tines 14 and 15 to maintain a magnetic field between the free ends of the tines 14 and 15. The pole-piece 27 is equipped with a shading coil 29 comprising a plurality of ring-like plates 30 of copper or other electrical conducting material, the pole-piece 27 extending through the central apertures in the ring-like plates 30. The function of the shading coil 29 is to produce eddy currents to bring the Q of the tuning fork of the switch to a required value.

The tines 14 and 15 may be set in vibration through suitable energization of an operating coil 31 mounted exterior of the casing 7 and extending around the casing 7.

Tuning bars 32 and 33 are provided on the tines 50 14 and 15 respectively in order that the tines 14 and 15 may be tuned as required to vibrate at a predetermined frequency. The tuning bar in each case is a place of wire mounted on the tine and extending laterally across the tine and has free end portions 34 and 35 extending outwardly be-

beyond edge portions of the tine. The tuning bars 32 and 33 are located near the free ends of the respective tines 14 and 15 and each tuning bar forms, in effect, a loading member on the tine. By bending the free ends 34 and 35 of a tuning bar to make the free ends 34 and 35 extend in various angular directions relative to the tine the loading effect and hence the frequency of the tine may be changed as required. More than one tuning bar may be used on each tine.

The tuning bar 33 on the tine 15 is utilized as a contact piece and is moved by action of the tine 15 relative to a spring wire contact 36, one end of which is secured to a strip 37 of conducting material.

The strip 37 of conducting material has a portion 38 embedded in an insulating block 39 mounted on a beam 40, spaced arm portions 41 and 42 of the beam 40 being embedded in the insulating block 39 and in spaced relation with the strip 37 as shown clearly in Fig. 6. As shown in Fig. 2 the beam 40 is mounted at one end on the upper portion of the tuning fork structure 13 and extends downwardly therefrom almost to the plug 9. The upper end portion of the beam 40 is held in place by screws 43 and 44 and is spaced from the tine 15 by an apertured spacer plate 45 disposed between the beam 40 and the tine 15. The screws 43 and 44 as shown in Fig. 5 extend through apertures in the beam 40, the spacer plate 45, the tine 15, spacer block 16, tine 14, spacer plate 17 and into screw-threaded engagement with the conducting bar 12. An elongated aperture 46 as shown in Figs. 2 and 3 is formed in the beam 40 to create the spaced arm portions 41 and 42 and to provide a space for accommodation of the strip 37 and the spring wire contact 36. The elongated aperture 46 in the beam 40 is defined by an elongated boss 47 formed on portions of the spaced arm portions 41 and 42 and at points where the spaced arm portions 41 and 42 terminate. The boss 47 serves to strengthen the arm portions 41 and 42. The beam 40 extends in spaced relation with and alongside the tine 15 and across the position of the tuning bar 33. At points where the arm portions 41 and 42 cross over the position of the tuning bar 33 the arm portions 41 and 42 are bent outwardly to provide offset portions 48 and 49 respectively to avoid engagement with the tuning bar 33 and allow operating space for the tuning bar 33 when the tine 15 is vibrating.

The lower end portion 50 of the beam 40 is movably supported on an adjustment screw 51 which is in screw-threaded engagement with the conducting bar 12 and a lock nut 52 bearing on an apertured conducting plate 53 in contact with the conducting bar 12. The conducting plate 53 is equipped with a lug 54 which is electrically connected through a lead wire 55 with the pin-type terminal 10. A spring 56 is disposed between the lower end portion 50 of the beam 40 and the lock nut 52. By suitably turning the adjustment screw 51 the lower end portion 50 of the beam 40 may be moved relative to the conducting bar 12. The lock nut 52 operates to hold the adjustment screw 51 in adjusted position and holds the apertured plate 53 pressed against the conducting bar 12.

The strip 37 of conducting material has a bent lower end portion 57 electrically connected through a lead wire 58 with the pin-type terminal 11. The upper end portion of the strip 37 terminates in an L-shaped finger portion 59, the shorter arm portion 60 of which extends over

a portion of the free end of the tine 15 and almost to the tuning bar 33. The spring wire contact 36 is secured at one end 61 to the strip 37 and extends over the finger portion 59 and the arm portion 60 and from thence to a position overlying the tuning bar 33. The spring wire contact 36 is pretensioned toward the tuning bar 33 but is normally held in spaced relation with the tuning bar 33 by the shorter arm portion 60 of the L-shaped finger portion 59. When the tine 15 is vibrated it moves the tuning bar 33 toward and away from the free end portion of the spring wire contact 36. During part of one-half cycle of movement of the tine 15 the tuning bar 33 makes contact with the free end portion of the spring wire contact 36 and flexes the spring wire contact 36. When the tine 15 swings back in its other half cycle of movement to carry the tuning bar 33 away from the spring wire contact 36 the shorter arm portion 60 of the L-shaped finger portion 59 serves as a stop to prevent the spring wire contact 36 from completely following the movement of the tuning bar 33. When the tuning bar 33 is in contact with the spring wire contact 36 the circuit through the relay is as follows: pin-type terminal 10, lead wire 55, lug 54, conducting plate 53, conducting bar 12, closed end of tuning fork 13, tine 15, tuning bar 33, spring wire contact 36, strip 37, lead wire 58 to pin-type terminal 11.

As above mentioned the tuning bars 32 and 33 may be adjusted to tune the respective tines 14 and 15 to a precise required frequency by bending free ends of the tuning bars 32 and 33 to make the free end portions 34 and 35 extend more or less angularly with respect to the tine on which the tuning bar is secured, possible different directions of bending of the free end portions of a tuning bar being indicated by dotted lines 62 in Fig. 3.

The adjustment screw 51 may be adjusted to change the normal spacing of the spring wire contact 36 relative to the tuning bar 33. The casing 7 may be removed from the plug 9 to provide access to the parts housed in the casing 7 but is normally held against undue removal by inward embossings 63 formed in the lower end of the casing 7 and pressed into recesses 64 formed in the plug 9.

The relay shown in the drawing is equipped with the pin-type terminals 10 and 11 so that it may be readily mounted in a supporting socket, not shown, but having jack-type terminals to receive the pin-type terminals 10 and 11. The tines 14 and 15 are made from bar stock of metal composition as follows:

Nickel	42
Chromium	4.5 or 5.5 or 6.5
Titanium	2.5
Carbon	.06
Manganese	.4
Silicon	.5
Aluminum	.4
Iron, the remainder.	

The tines made of a metal composition as above set forth are heat treated.

All three of these compositions have a positive temperature coefficient of expansion which does not vary significantly with variations in the heat treatment and have a temperature coefficient of modulus of elasticity which can be controlled by heat treatment. The heat treatment involves conventional age-hardening steps 76 of heating to a high temperature, quenching, and

then heating to a lower temperature for the time required to cause precipitation of the desired amount of the hardening phase. By varying the time and temperature of this last heating step, the temperature coefficient of elastic modulus can be varied within limits. The alloy containing 6.5 per cent chromium can have its temperature coefficient of elastic modulus varied between -30 and -10 parts per million per degree centigrade by this method. Similarly, the alloy containing 5.5 per cent chromium can have its coefficient varied between -10 and +10 parts per million per degree centigrade, and the alloy containing 4.5 per cent chromium can have its coefficient varied between +10 and +30 parts per million per degree centigrade.

Since the coefficient of elastic modulus can be varied without varying the coefficient of expansion, it is possible with various mechanical shapes to balance the two coefficients so that a temperature coefficient of frequency vibration can be produced which is substantially zero.

It is preferable to have the spacer block 16, the apertured spacer plate 17 and the apertured spacer plate 45 made of material having the same temperature coefficient of expansion as the material of the tines 14 and 15.

The conducting bar 12 is supported floatably so that under extreme temperature changes differences in expansion between the casing 7 and plug 9 and the conducting bar 12 will not cause forces which would bend the conducting bar 12 thus affecting the magnetic gaps between the tines 14 and 15 and the pole-piece 27 or the contact gap between the contact wire 36 and the tuning bar 33.

The conducting bar 12 is supported floatably also to prevent bending forces being transmitted to the conducting bar 12 by the assembly of the casing 7 to the plug 9 or by forces applied to the casing 7 in handling the relay when it is plugged in or out of its socket in use. The reason for floating conducting bar 12 is to prevent under temperature variations expansion stresses which would cause gap adjustment changes of the tines to the pole-piece 27 which would in turn cause a change in frequency. Also to prevent changes in the gap between wire 36 and contact 33 which would in turn cause a change in sensitivity of the relay.

Assuming that the operating coil 31 is energized with a current of required frequency and strength to set the tines 14 and 15 in vibration the tuning bar 33 will be moved in a series of movements into and out of contact with the spring wire contact 36.

What is claimed is:

1. A tuning fork-type switch comprising a vibratile tine, means to vibrate said tine, an adjustably supported beam extending alongside and in spaced relation with said tine, spaced arms on said beam extending in parallel relation with each other, a block of insulating material supported by said arms and embracing said arms and extending across the space between said arms, a metal strip supported by and extending through and from said block and into the space between said arms and a spring wire supported on said metal strip and extending into the path of movement of said vibratile tine.

2. A tuning fork-type switch comprising a vibratile tine, a contact on said tine, means to vibrate said tine, a beam secured at one end to an end portion of the tuning fork structure and

extending alongside and in spaced relation with said vibratile tine, spaced arms on said beam extending in parallel relation with each other, a block of insulating material secured to said arms and extending across the space between said arms, a conducting strip supported in and extending from said block and into the space between said arms and a spring wire secured at one end to said conducting strip and having a free end portion extending beyond said conducting strip and into the path of movement of said contact on said tine.

3. A tuning fork-type switch comprising a vibratile tine, a tuning bar of conducting material supported on said tine and extending across said tine, means to operate said tine, a beam secured at one end and extending alongside and in spaced relation with said tine and across the position of said tuning bar, spaced arms on said beam extending in parallel relation with each other and having offset portions in by-pass of said tuning bar, a block of insulating material secured to and supported by said arms and extending across the space between said arms, a conducting strip supported in said block and in spaced relation with said arms, an L-shaped finger portion on said conducting strip extending into the space between said arms and a spring wire contact secured at one end to said conducting strip and resting on said L-shaped finger portion and extending beyond said L-shaped finger portion and into the path of movement of said tuning bar on said tine.

4. An electrical switch comprising a tubular casing, a tuning fork structure housed in said tubular casing, a plug in one end of said tubular casing, a conducting bar loosely supported at one end in said plug and extending into said tubular casing and alongside said tuning fork structure, means securing the closed end portion of said tuning fork structure to an adjacent end portion of said conducting bar and a spider-type plate of spring sheet material loosely supported on the closed end portion of said tuning fork structure and said conducting bar, said spider-type plate having formed therein a relatively large aperture through which said conducting bar extends and having leg members in frictional engagement with the inner surface of said tubular casing.

5. A tuning fork-type relay comprising a pair of spaced vibratile tines, electrically energizable means to vibrate said tines, a permanent magnet, a pole-piece extending from said permanent magnet into the space between said tines, said permanent magnet and said pole-piece producing a magnetic field for said tines and a shading coil means supported on and encircling said pole-piece for producing eddy currents to bring the Q of the relay to a required value.
